UNITED STATES PATENT OFFICE.

ALBERT W. CHASE, OF CATSKILL, NEW YORK.

DRIVING MECHANISM FOR MOTORS.

1,324,384.

Specification of Letters Patent.

Patented Dec. 9, 1919.

Application filed January 13, 1917. Serial No. 142,165.

To all whom it may concern:

Be it known that I, ALBERT W. CHASE, a citizen of the United States of America, and a resident of Catskill, county of Greene, 5 State of New York, have invented certain new and useful Improvements in Driving Mechanism for Motors, of the which the following is a specification.

My invention relates to driving mechanism for motors, and is especially applicable to driving mechanism employing a plurality of worms for driving at different speeds.

Its object is to improve and simplify the connections between the driving shaft or 15 motor and a plurality of worms for driving the differential, for example, of a motor; to perfect means for bringing the clutch member of the driving shaft more readily into alinement with any one of the driving 20 worms, to perfect such alinement; and to render easier and more certain in operation the connecting of the clutch members of the various parts together and generally to make such parts easier to manipulate.

It consists of the novel devices and combinations herein shown and described.

In the drawings accompanying this specification and forming part hereof, I have shown my improvement in its preferred 30 form, as applied to driving the differential of a motor.

Referring now to this preferred form and to the drawings illustrating it,

Figure 1 is a plan view of the chassis of a 35 motor embodying my invention, some parts being partly broken away and others in section;

Fig. 2 is an enlarged longitudinal section taken on the line 2—2 of Fig. 1;

Fig. 3 is an enlarged horizontal view, in 40 section, taken on the line 3—3 of Fig. 4;

Fig. 4 is a transverse section taken on the line 4—4 of Fig. 1;

Fig. 5 is a horizontal section taken on the 45 line 5—5 of Fig. 6, certain parts being removed and other parts broken away, for the sake of clearness;

Fig. 6 is an elevation, in section, partly broken away, taken on the line 6—6 of 50 Fig. 5;

Fig. 7 is a detailed section taken on the line 7—7 of Fig. 6;

Fig. 8 is a longitudinal vertical section, 55 partly broken away, and substantially taken on line 8—8 of Fig. 1;

Fig. 9 is a detailed vertical section taken on the line 9—9 of Fig. 8;

Fig. 10 is a top view of the gear shift plate, showing controlling lever in neutral position;

Fig. 11 is a detailed section taken on the line 11—11 of Fig. 8.

My invention is shown in connection with the differential of a motor driven at different speeds by worms and worm gears. Three 65 worms, 1, 1, are shown, with their accompanying worm wheels 2, 2, giving two speeds forward and one in reverse. Each worm wheel 2 is connected to and drives a differential, of which 3 is the gear case. The 70 differential is provided with the usual parts, and will, therefore, not be further described, the differential driving in the usual way, divided rear axle 4 carrying the rear wheels 75 of the motor. The main driving shaft 5 of the motor is provided with a clutch member 6, adapted to engage any one of the clutch members 7, 7, of the different worms when the clutch member 6 is brought into alinement with such clutch member 7 and is forced 80 into connection with it. The means for forcing clutch member 6 into engagement with the clutch member 7 when in alinement with it consists of a lever 8, fast on a rock shaft 9, this latter carrying dependent arms 85 10, 10, extending between collars 11, 11, on a sleeve 12, fast to shaft 5. Lever 8 is shown as a hand lever for convenience, although ordinarily employed as a pedal. In the usual 90 way, the rocking of this lever throws shaft 5 backward or forward, causing clutch 6 to be thrown into or out of engagement with one of the clutches 7. 13, 13, are antifriction rollers, mounted in the dependent arms 95 10, 10.

Shaft 5 is connected at one end to the source of power, in the usual way, by a universal joint 14, and the other end of the shaft is connected by universal joint 15 with clutch 6. Shaft 5 is free to move in the 100 plane of the worms 2, 2, so as to bring clutch 6 opposite any one of the clutches 7. As shown, this movement is a horizontal one. This movement is controlled through controlling hand lever 16, mounted in the usual way in an H-box 17. It is loosely mounted, by pin connection with rock shaft 18, the connection being such that lever 16 may have a slight lateral movement, to accommodate itself to the different spaces in the H-box. 110

Fast on rock shaft 18 is a dependent arm 19, to the lower end of which is pivoted the link 20. This link, at its further end, is fastened to a rock shaft 21. This rock shaft 5 has pivoted to it at each end an arm 22. Each arm 22 is fast to a pin 23, mounted loosely in the framework, and at the inner end of each pin 23 is fastened an arm 24. The rear ends of the arms 24, 24, move 10 freely on pins 25, 25, fast in reciprocating bearing box 26, which carries the clutch member 6.

Bearing box 26 is mounted on guideways 27, 27, and is free to move horizontally 15 along these guideways. Forming part of the guideways is a fin 28, provided with a cutaway portion 29 opposite each clutch 7, having a curved surface corresponding to the curvature of clutch 6. Three of these 20 cutaway portions 29, 29, are shown, each one corresponding to a clutch 7 and being in perfect alinement with it.

Bearing box 26 is free to move horizontally along its guideways and the fin 28, 25 and whenever it is in perfect alinement with a clutch 7, the clutch 6 can be forced forward, in the manner already described, to engage with the corresponding clutch 7. At all other points in the lateral movement of 30 bearing box 26, no such forward movement of clutch 6 can take place, as some portion of clutch 6 will strike the fin 28. Thus, perfect alinement is always secured between clutch 6 and clutch 7 before engagement between them can be made. It will also be noted that bearing box 26 is always held in the same relative position to the clutches 7, the face of the box and the face of its accompanying clutch 6 being always exactly 35 parallel to the faces of the clutches 7.

30 is a ball bearing between the non-revoluble parts of box 26 and the rotating clutch 6.

In order to insure ease of manipulation 45 and more perfect alinement, I provide each clutch 7 with a cone-shaped projection 31 and clutch 6 with a cone-shaped depression 32.

It will be understood from the above that 50 the bearing box 26 and clutch 6 are free to move laterally along their guides, so as to bring clutch 6 into alinement with any clutch 7. When in such alinement, clutch 6 can be forced forward by means of lever 55 8 acting upon shaft 5 to cause clutch 6 to engage with the opposite clutch 7 and thus drive the corresponding worm wheel and differential. The curved cutaway portions 29 of fin 28 permit such movement of clutch 6, and these surfaces, coöperating with the curved surfaces of clutch 6 and the taper or cone surfaces 31 and 32, permit such movement when perfect alinement is obtained and insure easy and efficient operation. 65

In order to reduce the extent of the lateral or horizontal movement of the clutch and its bearing box, I preferably mount the worms with their ball bearings in a staggered arrangement, such as is shown in 70 Fig. 3. The ball bearings 33 of the middle worm, as there shown, are in substantially the same alinement as the inner part of the ball bearings 34, 34, of the two outer worms. The ball bearings of one of the worms thus 75 overlaps a portion of the ball bearings of the outer worms. This makes the worms much more compact in space, and materially reduces the extent to which the driving axle has to be swung at its free end. 80

In order to support and strengthen the driving shaft 5, I preferably provide an intermediate bearing capable of a slight movement in the plane of the shifting of the driving shaft needed to bring clutch 6 into 85 engagement with the different clutches 7. In the drawings, this consists of a ball bearing 35 having a slight lateral play to accommodate this lateral movement of the shaft. It consists of a ball bearing mounted in a laterally sliding piece 36, sliding in guides in a support 37 carried by yoke 38. Yoke 38 has two arms 39, 39, loosely mounted on arms 40, 40, secured to the chassis, so that the yoke will be free to tilt or rotate 95 on its central axis slightly as one side or the other of the chassis is raised.

Shaft 5 has a square portion 41, fitting into a square socket 42, to permit the backward and forward motion of the shaft in 100 coupling or uncoupling the clutches with one another.

My improvement furnishes a strong, accurate and reliable means for connecting the clutch of the driving shaft of a motor 105 with the clutches of a plurality of worms. It enables the operator to easily and accurately shift from worm to worm to change the speed or reverse the motor. It secures perfect alinement between the clutches, preventing any attempt at their connection unless the parts are properly alined, thus reducing the wear on the clutches and driving parts and the liability of breakage. It enables the practical use of a plurality of 110 worms and worm wheel drives in a motor for securing different speeds, with all the consequent advantages of lighter weight, less noisy operation, reduction of strain, ease of manipulation, with increased efficiency of drives, dispensing with the multiplicity of gears now usual in motor drives. 115

It will be noted that, while the shaft clutch is always connected with the shaft to rotate therewith, yet, through the operation 125 of the clutch bearing box and its guides, the shaft clutch member always remains with its axis parallel to the axes of the worms, and is thus always ready, when brought into alinement with a worm, to en- 130

gage with the clutch of that worm, and this notwithstanding the swinging of the driving shaft.

What I claim as new and desire to secure 5 by Letters Patent is:—

1. In the driving mechanism of a motor vehicle having a differential, the combination of a plurality of worms arranged side by side and each adapted to drive the differential of the motor at a different speed, a driving shaft pivotally mounted and having a free end adapted to swing in the plane of the worms, a clutch member connected to the free end of the shaft and adapted to 10 rotate therewith, a clutch bearing box for supporting the clutch member adapted to move across the ends of the worms at right angles to their axes, means for forcing the clutch member into engagement with any 15 worm, and an alining fin between parts of the clutch member and the ends of the worms provided with an opening opposite the end of each worm in exact alinement therewith, the said openings having the same 20 contour as the contour of the said parts of the clutch, whereby the clutch member cannot be forced into engagement with the worm until in exact alinement therewith.

2. In the driving mechanism of a motor vehicle having a differential, the combination of a plurality of worms arranged side by side and each adapted to drive the differential of the motor at a different speed, a driving shaft pivotally mounted and having a free end adapted to swing in the plane of the worms, a clutch member on the free end of the shaft, connected with the shaft so as to rotate therewith, a clutch member on the end of each worm, means for causing 25 the shaft clutch member and the clutch member on any worm in alinement therewith to engage with each other, the shaft clutch member and each worm clutch member having respectively a cone-shaped projection on 30

one of said parts, and a corresponding cone-shaped depression on the other of said parts adapted to coöperate to aline the two clutches when brought together.

3. In the driving mechanism of a motor vehicle having a differential the combination of three or more worms arranged side by side parallel with one another and each adapted to drive the differential of the motor at a different speed, ball bearings for each of the worms, the ball bearings of one or more of the worms being superimposed upon a portion of the ball bearings of one or more of the other worms, a driving shaft pivotally mounted and having a free end adapted to swing in the plane of the worms, 50 and a clutch member on the free end of the shaft adapted to be rotated thereby and also adapted to be brought into operative engagement with any of the worms.

4. In the driving mechanism of a motor vehicle having a differential, the combination of a plurality of worms arranged side by side and each adapted to drive the differential of the motor at a different speed, a driving shaft pivotally mounted and having a free end adapted to swing in the plane of the worms, a clutch member connected to the free end of the shaft and adapted to rotate therewith, means for forcing the clutch member into engagement with any worm, and an alining fin between parts of the clutch member and the ends of the worms provided with an opening opposite the end of each worm in exact alinement therewith; the said openings having the same 55 contour as the contour of the said parts of the clutch, whereby the clutch member cannot be forced into engagement with the worm until in exact alinement therewith.

In testimony whereof I have signed my name to this specification.

ALBERT W. CHASE.
